(57) **CLAIM**

The ornamental design for a photovoltaic module, as shown and described.

DESCRIPTION

FIG. 1 is a front, top and right perspective view of a photovoltaic module showing the new design;

FIG. 2 is a back, bottom and left perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof;

FIG. 8 is a bottom plan view thereof; and,

FIG. 9 is an enlarged view of the encircled area 9 shown in FIG. 1.

The evenly spaced broken lines illustrate features of the photovoltaic module which form no part of the claimed design.

The dash-dot broken lines in FIG. 1 and FIG. 9 illustrate the boundaries of the enlarged view and form no part of the claimed design.

The portions of the photovoltaic module within the dash-dot-dot broken lines in FIGS. 1, 3, and 9 illustrate features of the photovoltaic module which form no part of the claimed design.
